UNITED STATES PATENT OFFICE.

HERMANN SCHUPPISER, OF ZURICH, SWITZERLAND.

GAS-REGULATOR FOR INCANDESCENT LIGHTS.

No. 823,084.

Specification of Letters Patent.

Patented June 12, 1906.

Application filed April 7, 1905. Serial No. 254,296.

To all whom it may concern:

Be it known that I, HERMANN SCHUPPISER, a citizen of the Republic of Switzerland, residing at Zurich, in Switzerland, have invented new and useful Improvements in Gas-Regulators for Incandescent Lights, of which the following is a specification.

Gas-consumption regulators in which the gas-supply to the burner is regulated by means of a bell-valve introduced into the mixing-tube through the mouth of the jet and which is adjustable relatively to a valve-cone so that the width of the opening is varied in proportion to fluctuations of pressure of the gas present are known. In these regulators a regulation of the gas consumption only takes place and not a regulation of the air-supply to the mixing-tube.

According to the present invention the bell-valve is guided upon a valve-pin and is so arranged that it simultaneously regulates the amount of air supplied to the mixing-tube, so that an approximately constant mixing ratio is maintained between the amount of gas and air supplied to the mixing-tube. For this purpose the bell-valve is arranged to work in a conically-widening mixing-tube.

The accompanying illustrative drawings show one construction of the improved regulator.

Figures 1 and 2 are central vertical sections through the regulator, with portions thereof in elevation. In Fig. 2 parts are shown displaced by the gas-pressure. Fig. 3 is a horizontal section corresponding to the line A B of Fig. 1; and Fig. 4 is a plan, the parts being in the same position as that they occupy in Fig. 3.

The regulator is arranged in a casing that is formed with a vertical screw-threaded hole b for attachment onto a gas-pipe and with a funnel-shaped enlargement with which the hole b is in communication. Steps c are turned in the wall of this funnel-shaped enlargement, and upon these steps rest weights formed as disk-rings d. The lower portion of a vertically-movable bell f extends through the rings d, while the upper portion of said bell extends closely through a head or cap e, screwed onto the casing a. At its lower end the bell f has a flange g, which is located below the lowest or first weight d.

h indicates a regulating-pin carried by the casing a and extending centrally through the bell, its upper end being formed with a cylin-

drical head i, that closely fits the central opening in the top of the bell through which it extends. The head i, which acts as a guide to the upper part of the bell, has formed 60 round its periphery five equally-distributed vertical gas-outlet grooves k, each increasing in depth downwardly. Ribs l at the lower part of the pin h form gas-passages n between them and also serve to guide the lower 65 part of the bell.

Upon the head or cap e is arranged a mixing-tube m, the central axis of which coincides with the central axis of the bell f and which at its lower part has a conical form 70 corresponding to the upper part of the bell. The inclination of the conical portion of mixing-tube is similarly directed, but at a different angle to the inclination of the conical upper part of the bell.

The operation of the improved regulator is as follows: Gas flows through the passages n into the bell f and through the five outlet-openings surrounding the head i and formed by the grooves k and the opening provided 80 for the passage of the regulating-pin head i in the top of the bell into the mixing-tube m for the purpose of being there mixed with a suitable quantity of air. The weight of the bell corresponds at this time to a determined pressure—say that corresponding to a twenty-millimeter water-column—below which the gas-pressure is not able to lift the bell or 85 below which the bell remains in the position shown in Fig. 1. If now the gas-pressure increases—say from that corresponding to a twenty-millimeter water-column to that corresponding to a thirty-millimeter water-column—the bell will be lifted until by its flange g it lifts the first weight, so that the 90 bell will be then weighted by a certain amount, and it is thereby able to exert counter-pressure to the gas-pressure corresponding to a thirty-millimeter water-column and remain in its raised position. The lifting of 100 the bell has caused it to move upon the head i, whereby the five gas-outlet openings k have become smaller, because the grooves decrease in depth toward the top. If the gas-pressure still increases, the bell f rises 105 still more, all the weights being ultimately raised thereby one after the other. (See Fig. 2.) With the rise of the bell the cross-section of the five gas-outlet openings k decreases more and more.

The grooves k in the head i are arranged in such manner that the product of the outflow-

speed of the gas and the cross-section of the outlet-openings formed by the grooves *k* and the bell is constant in any position of the bell. For the production of a uniform flame correct regulation of the air-supply to the mixing-tube is also necessary in addition. This regulation of the air-supply is effected by making the upper part of the bell project into the conically-formed lower part of the mixing-tube, so that as the bell rises it decreases the annular space located between it and the mixing-tube more and more. By this means the speed of the air drawn in increases with the increased gas-pressure. By 15 suitably shaping the upper part of the bell, as well as the lower part of the mixing-tube, the speed and amount of the drawn-in air can be so controlled that the gas-and-air mixture is a good and efficient one at any gas-pressure, the complete combustion of the mixture being thereby insured. When the gas-pressure falls, the bell sinks and unloads itself gradually from the weights by depositing them upon the steps. The weights may 20 be so calculated that at a pressure corresponding to a thirty-millimeter water-column one weight is raised, and at each addition of pressure corresponding to a ten-millimeter water-column a further weight is raised in order to 25 be able to maintain with the bell the necessary counter-pressure to the gas-pressure.

Having now particularly described and ascertained the nature of the said invention and in what manner the same is to be performed, I declare that what I claim is—

1. A regulator for gas-burners comprising a casing having a gas-chamber and a supply-aperture, a hollow valve having an aperture in its top and normally seated over said supply-aperture, and a pin extending from the supply-aperture through the valve-aperture, said valve automatically movable along the pin by the gas-pressure to regulate the quantity of gas passing between the pin and the 45 wall of the surrounding valve-aperture.

2. A regulator for gas-burners, comprising a casing having a gas-chamber and a supply-aperture, a regulating-pin leading from the aperture through said chamber, a hollow 50 valve surrounding the pin normally seated over the supply-aperture and a cover on the casing to guide the valve when it is moved from its seat by the pressure of gas therein.

3. A regulator for gas-burners comprising a casing having a gas-chamber therein, a regulating-pin, a mixing-tube, and means operable by the gas-pressure in the chamber to regulate the gas and air supply.

4. A regulator for gas-burners comprising a casing having a gas-chamber therein, a regulating-pin, a mixing-tube, and a valve operable by the gas-pressure in the chamber to regulate simultaneously the gas and air supply.

65 5. A regulator for gas-burners comprising

a casing having a gas-chamber therein, a pin mounted in the latter and having a plurality of gas-channels formed therein, a perforated mixing-tube in communication with the gas-chamber, and means for automatically decreasing the quantity of air with the decreased supply of gas.

6. A regulator for gas-burners comprising a casing having a gas-chamber therein, a pin mounted in the latter having a plurality of converging grooves formed in its periphery, a hollow valve seated in the chamber surrounding the pin and adapted to be raised and lowered by the pressure of gas in the chamber and valve to vary the quantity of gas passing along the grooves.

7. A regulator for gas-burners comprising a casing having a gas-chamber therein, a pin mounted in the latter, having a plurality of converging grooves formed in its periphery, a 85 perforated mixing-tube communicating with the chamber, a valve seated in the chamber and provided with an aperture through which the pin projects, said valve being raised and lowered by the pressure of gas in the chamber to automatically diminish and increase the size of the openings formed by the wall of the aperture and the walls of the grooves.

8. In a regulator for gas-burners, a casing having a stepped chamber formed therein, a 95 cover for said chamber, a pin projecting through said cover having a plurality of gas-passages formed therein, a valve surrounding said pin and passages, and a weight on each of said steps adapted to be carried by said 100 valve, for the purpose set forth.

9. In a regulator for gas-burners, a casing having a stepped gas-chamber formed therein, a cover for said chamber, a pin mounted in the chamber having a plurality of downwardly-increasing peripheral gas-passages formed therein near its top, a bell-valve extending through the cover and surrounding the pin, a weight seated on each step and surrounding the valve, and means on the valve 110 for displacing the weights, for the purpose 110 specified.

10. In a regulator for gas-burners, a casing having a stepped gas-chamber, a cover therefor having a central opening, a stationary pin 115 concentrically mounted in the chamber and having a plurality of downwardly-increasing peripheral gas-passages formed therein near its top, a bell-valve of unequal cross-sectional area automatically movable through 120 said opening, and a mixing-tube of unequal cross-sectional area in communication with said chamber.

11. In a regulator for gas-burners, a casing having a stepped gas-chamber, a cover therefor having a central opening, a stationary pin 125 concentrically mounted in the chamber and extending through the cover and provided with a plurality of downwardly-increasing peripheral gas-passages near its top, a bell- 130

valve of unequal cross-sectional area automatically movable through said opening, an independent weight on each step of the chamber, a flange on the lower edge of the valve adapted to engage the lower weight, and a perforated mixing-tube of unequal cross-sectional area seated on said cover, substantially as and for the purpose specified.

In testimony whereof I have signed my name to this specification in the presence of two subscribing witnesses.

HERMANN SCHUPPISER.
